J. P. RUTH, JR

DISCHARGE FOR GRINDING MILLS

Filed June 12, 1923

Patented Nov. 24, 1925.

1,562,792

UNITED STATES PATENT OFFICE.

JOSEPH P. RUTH, JR., OF DENVER, COLORADO.

DISCHARGE FOR GRINDING MILLS.

Application filed June 12, 1923. Serial No. 644,892.

To all whom it may concern:

Be it known that I, JOSEPH P. RUTH, Jr., a citizen of the United States, and resident of the city and county of Denver, State of Colorado, have invented certain new and useful Improvements in Discharges for Grinding Mills; and I do declare the following to be a full, clear, and exact description of the invention, such as will enable others skilled in the art to which it appertains to make and use the same, reference being had to the accompanying drawings, which form a part of this specification.

The object of this invention is to provide a novel and efficient door or closure for discharge heads of grinding mills which may be held rigidly in position and will effectually prevent splashing and slopping of the pulp being discharged.

The invention comprises a closure which may have at its center an aperture for inspection of the interior of the mill and has at its back a protecting liner. Said closure also has an annular sleeve or drum, which may be cylindrical and is spaced from the discharge head by a spiral feed-screw carried by the outer walls of the sleeve and engaging the inner or discharge walls of the head. This feed screw prevents the pulp from passing from the mill in a direct line, causing it to travel a spiral path before passing over the discharge flange of the head. Thus the pulp is fed positively from the mill and at the same time splashing is prevented.

In the accompanying drawings wherein certain embodiments of the invention are disclosed by way of illustration,

Fig. 1 is an axial section through the discharge head of a mill provided with one form of closure of the present invention;

Fig. 2 is an outer end view thereof, the head being omitted;

Fig. 3 is a side elevation of the closure per se;

Fig. 4 is an axial section showing a slight modification;

Fig. 5 is an axial section showing a further modification.

The drawings disclose a discharge head 10 of a mill 12, said head having a discharge throat 14 which may be a journal for the mill and carries an outer discharge flange 15. The door or closure 16 of the present invention preferably is provided at its center with an opening 18 through which the in-

terior of the mill may be viewed. At the periphery said closure is provided with a preferably integral drum or sleeve 20 upon whose outer surface feed screws 22 are spirally arranged and are overlapped at least enough to prevent flow of pulp directly from the mill and cause the same to travel a spiral path. As shown three screw sections 22 are employed and each extends approximately half way around the drum 20. This construction positively feeds the pulp from the mill and prevents splashing. A liner 24 bolted to the rear of the closure 16 protects the latter from the balls or rods used in the mill. In the form of Figs. 1, 2 and 3, ears 25 on the outer end of the drum 20 are secured by bolts or screws 26 to lugs or bosses 28 integral with the flange 15. Thus the closure is held in position with the edges of the screw sections 22 in firm engagement with the inner discharge walls of the throat 14. If the lugs 28 extend inward toward the axis of the mill, the closure may be readily placed or withdrawn by slight rotation of the closure to cause the feed screws 22 to clear said lugs.

In the form of Fig. 5, a frusto-conical flange 30 integral with the drum 20 is substituted for the ears 25, the diameter of this flange being greater than the external diameter of the screws 22 and the internal diameter of the throat 14 engaged by said screws. The ends of feed screws 22 extend to and along the flange 30 and engage with the flange 15. Screws 32 are passed through the flange 30 and into lugs 34 on the flange 15 of the mill head, lugs 34 being low enough to avoid interference with feed screws 22 when the closure is being placed or removed.

In Fig. 4, the inner wall of the closure liner 124 is frusto-conical in shape to aline with the inner wall of the mill head 10, and the ends 122 of the feed screws 22 are correspondingly inclined. The transverse portion 16 of the closure may also be frusto-conical if desired, as shown. Spaced lugs 40 may be cast on the inner walls of the throat 14 to receive screws 42 passed through the drum 20 and retained by lock nuts 44. The closure may be rotated to clear the lugs 40 when being positioned or removed.

Thus in all the forms splashing is eliminated or reduced materially, while in the form of Fig. 5, where the pulp flows out between the frusto-conical flanges 15 and 30, splashing from any influences within the

2
mill is entirely prevented, at least so far as concerns the discharged pulp.

I claim:

1. In combination, a head for grinding mills having a discharge throat provided with an inner wall and a closure mounted in said throat, said closure comprising a transverse wall, a sleeve at the periphery of said wall spaced from the inner wall of the throat and having an outer wall, and a spiral feed screw carried by the outer wall of the sleeve and engaging the inner wall of the throat.
2. In combination, a head for grinding mills having a discharge throat, a closure mounted in said throat having a transverse wall, a liner on the inner face of said wall,

an annular member carried by said wall and spaced from the walls of the throat, and a spiral feed screw between said member 20 and the walls of the throat.

3. In combination, a head for grinding mills having a discharge throat provided with an inner wall, a removable closure mounted in the throat having a transverse 25 wall and a sleeve at the periphery of said wall spaced from the inner wall of the throat, a feed screw mounted on the sleeve between the sleeve and said inner wall, and a frusto-conical flange on the outer end of 30 said sleeve of greater diameter than the internal diameter of the throat.

In testimony whereof I affix my signature.

JOSEPH P. RUTH, JR.
